US0D1096960S

(12) **United States Design Patent** (10) **Patent No.:** **US D1,096,960 S**
(45) **Date of Patent:** **** Oct. 7, 2025**

(54) **TOSSING BALL WITH FINNED TAIL**

(71) Applicant: **Cassidy Labs, LLC**, Palo Alto, CA (US)

(72) Inventor: **Scott Cassidy**, Palo Alto, CA (US)

(73) Assignee: **Cassidy Labs, LLC**, Palo Alto, CA (US)

(**) Term: **15 Years**

(21) Appl. No.: **29/968,915**

(22) Filed: **Oct. 18, 2024**

(57) **CLAIM**

The ornamental design for a tossing ball with finned tail, as shown and described.

DESCRIPTION

FIG. 1 is a top front isometric view of a tossing ball with finned tail showing the design.

FIG. 2 is a bottom rear isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines in the drawings illustrate portions of the tossing ball with finned tail that form no part of the claimed design. The dash-dot broken lines in the drawings are boundary lines that form no part of the claimed design.

1 Claim, 7 Drawing Sheets
